US00D915634S

(12) **United States Design Patent** (10) Patent No.: **US D915,634 S**
Patterson (45) Date of Patent: ** *Apr. 6, 2021

(54) **TALL BAFFLE**

- (71) Applicant: **3FORM, LLC**, Salt Lake City, UT (US)
(72) Inventor: **Caleb Patterson**, Seattle, WA (US)
(73) Assignee: **3FORM, LLC**, Salt Lake City, UT (US)
(*) Notice: This patent is subject to a terminal disclaimer.
(**) Term: **15 Years**
(21) Appl. No.: **29/660,976**
(22) Filed: **Aug. 23, 2018**

(56)

CLAIM

The ornamental design for a tall baffle, as shown and described.

DESCRIPTION

FIG. 1 is a top front left perspective view of a tall baffle including my design;

FIG. 2 is a front elevation view thereof;
FIG. 3 is a rear elevation view thereof;
FIG. 4 is a left elevation view thereof;
FIG. 5 is a right elevation view thereof;
FIG. 6 is a top plan view thereof;
FIG. 7 is a bottom plan view thereof;
FIG. 8 is a top front left perspective view of an alternative embodiment of a tall baffle in which light is emitted from a top surface and bottom surface thereof including my design;
FIG. 9 is a front elevation view thereof;
FIG. 10 is a rear elevation view thereof;
FIG. 11 is a left elevation view thereof;
FIG. 12 is a right elevation view thereof;
FIG. 13 is a top plan view thereof;
FIG. 14 is a bottom plan view thereof;
FIG. 15 is a top front left perspective view of an alternative embodiment of a tall baffle in which portions are wrapped in felted polyethylene terephthalate (PET) including my design;
FIG. 16 is a front elevation view thereof;
FIG. 17 is a rear elevation view thereof;
FIG. 18 is a left elevation view thereof;
FIG. 19 is a right elevation view thereof;
FIG. 20 is a top plan view thereof;
FIG. 21 is a bottom plan view thereof;
FIG. 22 is a top front left perspective view of an alternative embodiment of a tall baffle in which portions are wrapped in felted polyethylene terephthalate (PET) and in which light is emitted from a top surface and bottom surface thereof including my design;
FIG. 23 is a front elevation view thereof;
FIG. 24 is a rear elevation view thereof;
FIG. 25 is a left elevation view thereof;
FIG. 26 is a right elevation view thereof;
FIG. 27 is a top plan view thereof; and,
FIG. 28 is a bottom plan view thereof.

The broken lines are included for the purpose of showing environmental portions of the tall baffle and form no part of the claimed design.
